UNITED STATES PATENT OFFICE

WILLIAM C. WHITWORTH, OF ATLANTA, GEORGIA

SASH PULLEY

Application filed June 13, 1930. Serial No. 460,978.

This invention relates to a sash pulley whereby a pair of window sashes can be provided with a flexible connection extending upwardly into the top of the frame so that the sashes will be balanced, and it becomes unnecessary to form the window frames with pockets or boxes such as commonly employed where sash weights are used.

It is another object of the invention to provide a pulley which can be positioned readily in the upper portion of a window frame, the fastening means employed for holding it in place being located where they are accessible readily at all times so that the pulley can be removed and a new flexible connection placed in position without mutilating the frame.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawing

Figure 1 is a section through the top portion of a window frame showing a sash pulley in position with a flexible sash connection mounted thereon.

Figure 2 is a section on line 2—2, Figure 1.

Figure 3 is a perspective view of the sash pulley.

Referring to the figures by characters of reference, 1 designates a portion of a window frame provided with the usual parting strips 2 forming guide channels 3 and 4 at the sides thereof in which the sashes 5 and 6 are adapted to slide. Holes 7 are cut in the top of the frame so as to open into the upper ends of the channels 3 and 4. In the drawing only

one of these holes has been illustrated but it is to be understood that one of them is to be located adjacent each side of the frame.

The sash pulley includes a corner bracket 8 which is so shaped as to fit snugly in the corner and is provided longitudinally of its top and side portions with channels 9 adapted to receive the adjacent portions of the parting strips 2. A yoke 10 is extended from the angle portion of the bracket and has a grooved wheel 11 mounted to rotate therein freely. Openings 12 are formed in the bracket so that a flexible connection 13 mounted on the wheel 11 can work freely within these openings. This connection is adapted to be secured to the respective sashes 5 and 6 so that each will act as a counterbalance for the other.

When it is desired to attach a sash pulley to the frame 1 a hole is cut into the top thereof as shown at 7 and the yoke 10 with connection 13 mounted on its wheel 11, is inserted upwardly into the opening until bracket 8 becomes seated snugly in the corner of the frame with the parting strips 2 in the channels 9. The bracket is then fastened in place by means of screws 14 or the like inserted into the side and top of the frame and after the connection 13 has been attached to the respective sashes the device is ready for use.

The fastening devices 14 can be easily reached for the purpose of detaching bracket 8 and withdrawing yoke 10 and wheel 11 from the opening 7.

What is claimed is:

1. A sash pulley including an angle bracket channeled in two directions for the reception of the top and side parting strips of a window frame, there being openings in the corner portion of the bracket at opposite sides of the channels, and a wheel supported above and between the openings and joined to the bracket.

2. The combination with a window frame having parting strips and an opening ex-

tending into the top of the frame at one corner thereof, of a corner bracket fitted snugly within the frame and straddling the parting strips, a structure integral with the bracket and extending into the opening, a wheel carried by said structure for supporting a flexible sash connection, and means for securing the bracket to the frame to support the wheel within the opening, there being openings in the bracket for receiving the flexible sash connection.

In testimony that I claim the foregoing as my own, I have hereto affixed my signature.

WILLIAM C. WHITWORTH.
